(57) **CLAIM**

The ornamental design for a tool handle, as shown and described.

DESCRIPTION

FIG. 1 is a perspective view of a tool handle showing the new design;

FIG. 2 is a left side view of the tool handle;

FIG. 3 is a right side view of the tool handle;

FIG. 4 is a bottom view of the tool handle;

FIG. 5 is an top view of the tool handle;

FIG. 6 is a front view of the tool handle;

FIG. 7 is a rear view of the tool handle; and,

FIG. 8 is a perspective view of the tool handle shown in use on a representative tool.

The broken lines shown illustrate portions of the tool handle and the representative tool that form no part of the claimed design.
